UNITED STATES PATENT OFFICE.

HERMAN OZLEK, OF PHILADELPHIA, PENNSYLVANIA.

SWING.

1,396,776.

Specification of Letters Patent.

Patented Nov. 15, 1921.

Application filed November 19, 1920. Serial No. 425,229.

To all whom it may concern:

Be it known that I, HERMAN OZLEK, a citizen of the United States, residing at Philadelphia, in the county of Philadelphia 5 and State of Pennsylvania, have invented certain new and useful Improvements in Swings, of which the following is a specification.

One object of my invention is to provide 10 an improved swing of the type including two opposed chairs or benches mounted on a frame; the parts being so arranged that the swing will be strong and durable and can be easily constructed at a low cost.

Another object is to so make my improved 15 swing that persons sitting in the chairs can easily effect a swinging movement.

A still further object is to make my invention in such manner that it will afford 20 amusement and will be safe for use by children.

These objects, and other advantageous 25 ends which will be described hereinafter, I attain in the following manner, reference being had to the accompanying drawings in which—

Figure 1 is a top plan view of a swing 30 constructed in accordance with my present invention.

Fig. 2 is a side elevation of the swing shown in Fig. 1,

Fig. 3 is a view of the same general character as that shown in Fig. 2 illustrating the parts in the position which they occupy 35 during the swinging movement of the chairs,

Fig. 4 is a sectional elevation taken on the line 4—4 of Fig. 1,

Fig. 5 is a transverse section taken on the line 5—5 of Fig. 1,

Fig. 6 is a fragmentary perspective view 40 of certain of the parts, and

Fig. 7 is a fragmentary detached perspective view showing certain of the constructive features of my invention which I preferably employ.

Referring to the drawings, 8 represents a base which may be made of longitudinally and transversely extending pieces of wood; said base having secured thereto two sets of 50 transversely opposed standards 9; the sets being positioned adjacent the opposite ends of the frame 8. The standards include comparatively wide portions 10 for a purpose hereinafter described. A frame 11 has two 55 chairs 12 mounted thereon at positions nor-

mally between the respective sets of standards 9 and a removable slat platform 13 is mounted on the frame between the chairs 12 so as to form a foot-rest for persons sitting in the chairs. Two substantially U-shape 60 suspension yokes 14, which are preferably made of heavy bar which is round in cross section, have their transversely extending bottom portions 15 rotatably mounted in the frame 11 below the seats 16 of the respective 65 chairs 12. The legs 17 of the suspension yokes 14 extend upwardly at right angles to the transversely extending bottom portions 15 and are normally positioned centrally of the widths of the standards 9 as clearly 70 shown in Figs. 2 and 4; said leg portions 17 being located between the respective chairs and the inner surfaces of the standards 9. The upper parts of the leg portions 17 fit within grooves 18 in wide blocks 19; 75 said grooves being made centrally within the inner surfaces of said blocks; the blocks being positioned at opposite sides of the chairs 12 between the respective sides of standards 9. The grooves 18 at their tops 80 terminate in holes 20 which extend transversely through the blocks 19 to the outer surfaces thereof as shown in Fig. 5. The upper ends of the legs 17 of the suspension yokes 14 are bent outwardly in sub- 85 stantially horizontal directions and provide trunnions 17^a which fit within sockets 21 extending downwardly from the tops of the standards 9 as clearly shown in Figs. 5 and 7; said sockets 21 being located centrally 90 within the widths of the respective standards. Retaining heads 22 cover the tops of the sockets 21 and may be secured to the tops of the standards 9 by nails or screws in order to prevent the trunnions from ac- 95 cidentally moving upwardly out of the sockets 21. The outer ends of the sockets are closed by caps 23 which may be made of wood either formed integral with the standards or glued or otherwise secured in position so as to cover the extreme ends of the trunnions and present an ornamental appearance.

If desired, clips 24, such as staples, can be driven into the blocks 19 so as to retain the leg portions 17 and trunnions 17^a in position. The blocks 19 have extensions 25 which normally extend in opposite directions as shown in Figs. 2 and 4 and as illustrated these extensions provide handles to be grasped by 110

the occupants of the chairs and may be made in any ornamental configuration such for example as the snakes' heads as illustrated.

To effect the swinging movement of the frame 11 and chairs 12, the occupants of the chairs can pull and push on the handles 25 and the leg portions 17 of the suspension yokes 14 will serve as levers to swing the frame 11 longitudinally in backward and forward directions; the trunnions forming pivotal bearings with the standards 9 and owing to the wide character of the portions 10, the leg portions 17 of the suspension yokes 14 will not be visible to any great extent viewed from the outside of the swing.

By having the leg portions 17 fitting within the grooves 18, a durable structure is provided since a long contact is provided between the blocks 19 and the leg portions. Furthermore by the provision of the trunnions and holes 20 relatively to the grooves 18, the parts may be easily and quickly secured together and can be cheaply manufactured. The trunnions 17 can be easily inserted and removed from the sockets 21; the heads 22 being separately attached as above described.

By the arrangement and construction of parts, a cheap but extremely durable swing is provided which requires comparatively little effort on the part of the occupants of the chairs to effect a swinging operation and a single pair of yoked suspension members is all that is necessary to provide the suspension means. By providing the wide blocks 19 and the wide portions of the standards 9, the yoked members are hardly visible, viewed from the outside of the chair and furthermore there are no parts which would injure the clothing of persons using the swing.

While I have described my invention as taking a particular form, it will be understood that the various parts of my invention may be changed without departing from the spirit thereof, and hence I do not limit my-

self to the precise construction set forth, but consider that I may make such changes and alterations as fairly come within the scope of the appended claims.

Having thus described my invention, what I claim as new and desire to secure by Letters Patent is:—

1. A swing including a base having laterally disposed pairs of standards; yoked suspension members having angularly extending trunnions rotatably mounted adjacent the tops of said standards; a swinging frame supported by said yoked members; and grooved members having handles, said yoked members having integral parts fitting within said grooves; substantially as described.

2. A swing including a base having laterally disposed pairs of standards; yoked suspension members having angularly extending trunnions rotatably mounted adjacent the tops of said standards; a swinging frame supported by said yoked members; and grooved members having handles, said yoked members having parts fitting within said grooves, said handle members having holes leading outwardly from said grooves and through which said trunnions extend; substantially as described.

3. A swing including a base having laterally disposed pairs of standards; yoked suspension members having angularly extending trunnions; a swinging frame supported by said yoked members; handle members secured to said yoked suspension members, said standards having sockets extending downwardly therein; and heads secured to said standards and forming covers for said sockets; substantially as described.

In testimony whereof I have signed my name to this specification in the presence of two subscribing witnesses.

HERMAN OZLEK.
